(57) **CLAIM**

The ornamental design for a food dehydrator, as shown and described.

DESCRIPTION

FIG. 1 is a top-front perspective view of a food dehydrator. FIG. 2 is a bottom-rear perspective view of the food dehydrator. FIG. 3 is a front view of the food dehydrator. FIG. 4 is a rear view of the food dehydrator. FIG. 5 is a right side view of the food dehydrator. FIG. 6 is a left side view of the food dehydrator. FIG. 7 is a top view of the food dehydrator; and, FIG. 8 is a bottom view of the food dehydrator.

(Continued)

The broken lines in the drawings depict portions of the food dehydrator that form no part of the claimed design.
